US00D707219S

(12) **United States Design Patent**
Kim

(10) **Patent No.:** **US D707,219 S**
(45) **Date of Patent:** ** *Jun. 17, 2014

(54) **CASE FOR ELECTRONIC DEVICE**

(71) Applicant: **Samsung Electronics Co., Ltd.,**
Suwon-si (KR)

(72) Inventor: **Yoon-Young Kim**, Seongnam-Si (KR)

(73) Assignee: **Samsung Electronics Co., Ltd.,**
Suwon-si (KR)

(*) Notice: This patent is subject to a terminal disclaimer.

(**) Term: **14 Years**

(21) Appl. No.: **29/448,701**

(22) Filed: **Mar. 13, 2013**

(51) LOC (10) Cl. **14-03**

(52) U.S. Cl.

USPC **D14/250**

(58) **Field of Classification Search**

(57) **CLAIM**

The ornamental design for a case for electronic device, as shown and described.

DESCRIPTION

FIG. 1 is a perspective view of a case for electronic device showing my new design with the case in an open state;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is a bottom perspective view thereof; and,

FIG. 10 is a perspective view thereof showing the case in a closed state.

The broken lines immediately adjacent the shaded surfaces represent boundaries of the claimed design. All other broken lines depict unclaimed environment. The broken lines form no part of the claimed design.

1 Claim, 10 Drawing Sheets
